FREDERICK A. FELDKAMP, OF NEWARK, NEW JERSEY, ASSIGNOR OF ONE-HALF TO HENRY BERG, OF ORANGE VALLEY, NEW JERSEY.

SYSTEM FOR THE IGNITION OF THE GASEOUS MIXTURES IN EXPLOSIVE-GAS ENGINES.

No. 892,038.

Specification of Letters Patent.

Patented June 30, 1902

Application filed August 24, 1907. Serial No. 390,016.

To all whom it may concern:

Be it known that I, FREDERICK A. FELDKAMP, a citizen of the United States, residing at Newark, in the county of Essex and State of New Jersey, have invented certain new and useful Improvements in Systems for the Ignition of the Gaseous Mixtures in Explosive-Gas Engines; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

My present invention has reference, generally, to a novel electrical system for the ignition of the gaseous - mixtures in explosive gas-engines by means of an incandescent body, such as a fine wire which is secured between the ends or poles of two electric conductors or electrodes of an igniting device, similar to the usual sparking device of a gas-engine.

With my present invention the main purpose is to provide a novel system in which the incandescence or glow of an incandescent body will be produced in an instantaneous and uniform or constant manner, substantially in the manner of an electric spark, the intermittent lighting-up and extinction of the incandescent body, by my present invention, being readily regulable, so as to take effect in quick or slow succession, according to the speed at which the engine is running, but the time of each glow or incandescence always being the same. In other words, instead of having an incandescent body brought to incandescence in the manner of the usual wire in an incandescent tube, an electric system has been produced in which the incandescent body or wire is made to glow for a very short time only, and is immediately extinguished, to be at once re-lighted, according to the rapidity with which the explosions of the gaseous mixture in the engine are desired, but each incandescent state of the wire always being of the same duration. It must therefore be evident, that the circuit must be closed by means of a timing device, which revolves, preferably upon the cam-shaft of the engine, the incandescent wire being very thin, so that it will flash up quickly, during each time that contact is made. It will also be

evident, that with automobiles, where the speed changes continually, other considerations have to be taken into consideration and that certain existing conditions have to be fulfilled, in order that a positive and properly working incandescent ignition device will be the result. With high speed, for instance, the time of contact is extremely short, and an electric current must be produced far in excess of the intensity of the current which would under ordinary conditions bring the wire to incandescence. Furthermore, an electric current which will perform its work satisfactorily at slow speed, will utterly fail to work at high speed, this latter condition being due to the fact that the time of contact is entirely too short to allow the electric current to perform its work during the short intervals of time elapsing between the rapidly succeeding contacts. It will also be evident, that if the current were regulated for high speed, then at low speed the igniting wire would burn out at once, because the excessive current acting satisfactorily during the short intervals of time, at high speed, would naturally destroy the thin wire during the longer periods of incandescence, at slow speed.

The principal object of my present invention, therefore, is to provide a means or system in which the electric current will act uniformly, at all times upon the thin wire, so that the period of incandescence will not vary, even if the time of making contact at the timing device is variable. Thus, it is the province of my present invention to provide a novel electric system, in which the incandescence or glow of the igniting wire never varies, no matter whether the contact is continuous and uninterrupted, as for instance when the engine is at a stand-still at the time that the timing device is making contact, or whether only short impulses are sent through the circuit, as is the case when running at high speed.

To overcome these objectionable features and to effect the result hereinabove stated, that is of the electric current at all times acting uniformly upon the thin igniting wire, I have constructed a secondary contact-making device, which is operated by the contact-making device operated from the cam-shaft of the engine.

The invention is clearly illustrated in the accompanying drawing, on which

Figure 1 is a diagrammatical view of the

igniting system, embodying the principles of the present invention, said view showing in connection therewith a sectional representation of a portion of the cylinder of an explosive gas-engine, and its igniting-plug which is represented in elevation. Fig. 2 is a sectional representation of a portion of the base of the apparatus and a spring-contact and bridge-piece arranged thereon.

10 Referring now to the said drawing, the reference-character 1 indicates a portion of the cylinder of an explosive gas-engine into which is screwed an ignition device 2, similar in construction to any one of the usual spark-plugs, provided with the usual electrodes 3 and 4, suitably insulated from each other in the usual manner, and projecting from the end of the device or plug within the explosion chamber or cylinder of the engine, substantially as illustrated.

20 The reference-character 5 indicates the incandescent or glow-wire, the same being suitably connected at its ends with the end-portions of the respective electrodes 3 and 4. 25 Leading from any suitable part, as 6, of the engine is a main wire 7, said wire being connected with the circuit-wire 8, having its one end-portion suitably connected with an electric-battery 9. Leading out of said battery 30 is a circuit-wire 10, which is attached to the fixed end-portion of a spring-contact 11, the normal initial position of said spring-contact being to establish electrical contact with a metal fixture or bridge-piece 12, and said 35 spring-contact being provided at its free end with a button 13, for depressing said spring-contact from its normal position, to break its electrical connection with said fixture or bridge-piece 12, and cause it to make electrical contact with a contact-post or button 40 14, as will be clearly evident, and for the purposes to be hereinafter more fully described. Leading from said fixture or bridge-piece 12 is a circuit-wire 15 which is connected at its 45 opposite end with the hub or other suitable part of a contact-producing device or brush 16, the same being preferably secured upon the cam-shaft 17 of the engine, so as to rotate with the same, but being insulated therefrom by means of an insulating sleeve or ring 18. The said rotary brush is operatively connected with the circuit making and breaking device 19, also termed herein as a timing device, the same comprising an insulated 55 member or element, as 20, which carries a metal contact-plate or block 21, with which the brush makes and breaks electrical contact, either slowly or rapidly according to the number of revolutions of the cam-shaft produced by the varying speeds of the engine. 60 The said contact-plate or block 21 is usually provided with a binding screw, as 22, to which is attached a circuit-wire 23, said wire being connected at its other end with the 65 post 24 on which is pivotally mounted or ful-

crummed a contact-bar or rod 25, for regulating the time of the current which passes through the igniting-circuit and the wire 5. Said bar or rod is provided with a short arm 26, with which is connected a spring 27, secured at its opposite end to an adjusting screw 28. Said screw turns in a screw-threaded bearing 29, suitably secured upon and insulated from the usual base or board 30. The said bar or rod 25 is also formed with a longer arm 31, which is provided with an adjustably arranged regulating and contact-establishing screw 32, and the free end-portion of said arm 31 is movably arranged between the end-portions of a pair of regulating screws 33 and 34, said screws being rotatably arranged in screw-threaded bearings 35 and 36, respectively, suitably secured upon and insulated from the base or board 30.

70 Under normal conditions, the free end-portion 37 of the screw 32, usually a platinum point, makes electrical contact with a contact-plate 38, also preferably of aluminum, which is suitably mounted upon the long arm 40 of another contact-rod or bar 39, said rod or bar being pivotally connected with or mounted upon a support or post 41. This rod or bar 39 is provided with a short arm 42 to which is connected, by means of a swivel 43, or other suitable means, a spring 44, said spring being attached at its other end to an adjusting or regulating screw 45, connected with the metal frame-plate or support 46, suitably secured upon and insulated from the base or board 30. An electric-circuit 100 is thus made through the arms of rod or bar 25, the screw 32, the arms of the rod or bar 39, and the spring 44, screw 45 and the plate or support 46. A main circuit-wire 47 is attached at one end with said plate or support 46, said wire being connected at its opposite end with the member 48 of the spark-plug, through which, and by means of the elements 3, 5 and 4, the main electric circuit is finally completed, through the engine and 110 the screw 6, and wire 7 with the main circuit-wire 8 and battery 9.

105 In any suitable portion of the circuit-wire 47 there may be arranged a switch 49, with the parts 50 and 51 to which the wire is connected, a switch-lever 52 being used to close the circuit, under normal conditions, between the parts 50 and 51.

115 Referring now again to the drawing, it will be seen, that I have attached to the post 24, a circuit-wire 53, which is connected with a reactance-coil 54 into which extends a movable core 55, said core being provided with a screw-threaded shank 56, movably arranged in a bearing 57, so as to be adjustable in and 120 out of said coil 54, as will be clearly evident. Leading from said coil 54 is a circuit-wire 58, terminating in this instance in two electro-magnets 59, in each of which is a core 61; and, leading from said electro-magnets is a 125 130

circuit wire 60, which completes the circuit finally through the wire 8, battery 9, wire 10, the spring-contact 11, wire 15, the circuit making and breaking device 19, and 5 wire 23 with the post 24, as will be clearly evident.

Having thus described the ignition circuit, as well as the magnet-circuit, it will be clearly seen from an inspection of the drawing, when the switch-lever 52 is making contact directly with the button 51, that the current as it passes through the magnet-circuit energizes the electro-magnets, whereby the cores of said magnets immediately attract the armature formed by the arm 40 of the rod or bar 39, and whereby the main ignition-circuit is broken or interrupted by the separation of the contacts 37 and 38, the parts being so regulated that the device will 15 operate most perfectly at high speed. The ignition and magnet-circuits are connected in parallel, and the resistance of the electro-magnets is such that they will attract the armature at high speed, while the igniting wire 5 will be brought to incandescence during this short interval of time. To find the point at which both circuits work well, the previously mentioned reactance coil, which is placed in the magnet-circuit, is provided 20 with the movable core for regulating purposes. Upon screwing this core further into this coil, electric current in the magnet circuit is decreased, while the current is increased in the igniting circuit. There may 25 be also arranged in the igniting circuit, any suitable-regulating device, either a variable resistance or a reactance coil, but generally this is unnecessary, and these devices being well known they are not shown in the accompanying drawings. In place of the high resistance-windings upon the magnets, a compound winding may be employed, where the heavy wire is connected in the ignition circuit. In that case the armature is attracted 30 to a great extent by the current in the ignition circuit, while the current in the fine wire not only attracts the armature, but holds it attracted, as long as the contact lasts at the timer between the elements 16 and 21.

Attention is called to the fact that the armature and contacts can be regulated in such a manner, that the time necessary for the armature-arm 40 to travel from the contact-making point or element 37 to the magnetic cores 61 may be greatly varied by various regulations or adjustments of the different screws 28, 32, 33 and 34. The purpose of such regulation is to allow the current to bring the wire 5 into proper and perfect 35 incandescence; the armature-arm 40 making electric contact with the point 37, during the time that the arm 31 travels the distance between the ends of the two oppositely located screws 33 and 34, after which the arm 40 is 40 allowed to travel the distance between the

point 37 and the ends of the magnetic cores 61, whereupon the ignition circuit becomes broken. By this means a very close regulation can be effected in the operating device, especially in conjunction with the reactance coil, as will be clearly understood. When in this manner once regulated, the device will respond with perfect action, and no further regulation is needed. The reactance coil may be regulated, at times, by 45 means of the adjustable core 55, when variations of the voltage of the battery may make such regulation necessary.

The operation briefly is as follows:—When contact is made by the timer upon the cam-shaft, the electric current passes partly through the magnet-circuit and partly through the ignition circuit. Immediately the incandescent wire 5 begins to glow, but at the same moment, before this incandescent state grows to a dangerous degree, the magnet has attracted the armature, owing to the construction and arrangement of the regulating devices, and the ignition circuit is interrupted.

It will be evident, that it will make no difference, whether the timer-contact is of long or short duration, corresponding to the rates of speed of the engine and cam-shaft, since this action affects merely the time during 50 which the armature is held attracted by the pole-pieces of the electro-magnets, it being clearly evident, that the time of electrical contact in the ignition circuit is always the same, owing to the regulable distance between the ends of the screws 33 and 34, no matter whether the timer makes contact of a long or short duration, and this is even so at such time when the brush 16 is stopped directly in its engagement with the contact 55 21, except that under this last condition the current will be consumed in the magnet-circuit, which at any rate is very small.

It is a self-evident fact, that the material of the igniting wire 5 must have a very high melting point, much higher than the ignition-point of the gases which are to be exploded; that it must not oxidize at high temperatures, and must be able mechanically to withstand any strain, and must, furthermore, not be brittle. The wire, also, must be very thin, that it will heat up very quickly in the shortest time. All of these conditions can be readily satisfied, since such material which will answer all these conditions is known.

From the foregoing description of my present invention it will be seen, that I have devised a novel and simple system for the purposes stated because there is no necessity of high tension coils, nor high tension currents; and furthermore, neither heavy insulation, spark coil, nor movable contacts inside of the cylinder are required.

The usual spark-plug troubles are also

overcome, since in this case a carbon deposit will do no harm, firstly, because the current is of low tension, and secondly, any deposit will burn off the wire, without harm to the wire.

If desired, the switch-block 49 may be provided with another contact or button 62, upon which the switch-lever 52 can be turned so as to throw the wire 47 in circuit 5 with the wire 60, by means of a circuit wire 63 in which is disposed an incandescent test-wire 64 of the same degree of incandescence as the igniting wire 5 within the cylinder of the engine, said test-wire 64 being inclosed 10 in a glass bulb 65 of the usual incandescent lamp-construction. By pressing the free end-portion of the spring-contact 11, previously mentioned, upon the contact 14, a circuit is established by means of a wire 66, 15 which is connected with said contact 14 and with the circuit-wire 23, both the igniting device and its wire 5, as well as the timing device 19 being cut out of circuit, as long as said spring-contact 11 is pressed down, as 20 will be clearly evident.

I claim:

1. In an igniting system for explosive gas-engines, the combination with a portion of the cylinder of the engine, and an igniting device 30 connected therewith, of an incandescent body carried by said device, an electric ignition circuit in which said igniting device and incandescent body are disposed, a circuit-completing and breaking device in said circuit, comprising a rotary means which is subject to variable speeds, instrumentalities in 35 said electric circuit for producing the incandescence of said incandescent body, and a magnet-circuit in parallel with said ignition 40 circuit, provided with electro-magnets and a re-actance coil in said circuit, all arranged to extinguish said incandescent body after a constant time interval irrespective of the varying speeds of the rotary contacting means 45 of said circuit-completing and breaking device, substantially as and for the purposes set forth.

2. In an igniting system for explosive gas-engines, the combination with a portion of 50 the cylinder of the engine, and an igniting device connected therewith, of an incandescent body carried by said device, an electric ignition circuit in which said igniting device and incandescent body are disposed, a circuit-completing and breaking device in said circuit, comprising a rotary means which is subject 55 to variable speeds, instrumentalities in said electric circuit for producing the incandescence of said incandescent body, and a magnet-circuit in parallel with said ignition circuit, provided with electro-magnets and a reactance coil in said circuit, all arranged to extinguish said incandescent body after a constant time interval irrespective of the varying speeds of the rotary contacting 60 device, substantially as and for the purposes set forth.

3. In an igniting system for explosive gas-engines, the combination with a portion of the cylinder of the engine, and an igniting device connected therewith, of an incandescent body carried by said device, an electric ignition circuit in which said igniting device and incandescent body are disposed, a circuit-completing and breaking device in said circuit, comprising a rotary means which is subject to variable speeds, a metal frame-plate in 80 said circuit, electro-magnets mounted upon said frame plate, an oscillating armature in said circuit, adapted to be attracted by said electro-magnets, and means also in said circuit, arranged to maintain a complete electric circuit with said armature during a portion of its movement, but breaking said electric circuit during the remainder of the movement of said armature, all arranged to produce the incandescence of said incandescent body, and at a predetermined time extinguish the same irrespective of the varying speeds of the rotary contacting means of said circuit-completing and breaking device, substantially as and for the purposes set forth.

means of said circuit-completing and breaking device, and adjustable regulating devices for varying the time of incandescence of said incandescent body, substantially as and for the purposes set forth.

3. In an igniting system for explosive gas-engines, the combination with a portion of the cylinder of the engine, and an igniting device connected therewith, of an incandescent body carried by said device, an electric ignition circuit in which said igniting device and incandescent body are disposed, a circuit-completing and breaking device in said circuit, comprising a rotary means which is subject to variable speeds, a metal frame-plate in 70 said circuit, electro-magnets mounted upon said frame plate, an oscillating armature in 75 said circuit, adapted to be attracted by said electro-magnets, and means also in said circuit, arranged to maintain a complete electric circuit with said armature during a portion of its movement, but breaking said electric circuit during the remainder of the movement of said armature, all arranged to produce the incandescence of said incandescent 80 body, and at a predetermined time extinguish the same irrespective of the varying speeds of the rotary contacting means of said circuit-completing and breaking device, substantially as and for the purposes set forth.

4. In an igniting system for explosive gas-engines, the combination with a portion of the cylinder of the engine, and an igniting device connected therewith, of an incandescent body carried by said device, an electric ignition circuit in which said igniting device and incandescent body are disposed, a circuit-completing and breaking device in said circuit, comprising a rotary means which is subject to variable speeds, a metal frame-plate in 100 said circuit, electro-magnets mounted upon said frame plate, an oscillating armature in said circuit, adapted to be attracted by said electro-magnets, means also in said circuit, arranged to maintain a complete electric circuit with said armature during a portion of its movement, but breaking said electric circuit during the remainder of the movement of said armature, all arranged to produce the incandescence of said incandescent body, and at a predetermined time extinguish the same irrespective of the varying speeds of the rotary contacting means of said circuit-completing and breaking device, substantially as and for the purposes set forth.

5. In an igniting system for explosive gas-engines, the combination with a portion of the cylinder of the engine, and an igniting device connected therewith, of an incandescent body carried by said device, an electric ignition circuit in which said igniting device and incandescent body are disposed, a circuit-completing and breaking device in said circuit, comprising a rotary means which is subject to variable speeds, a metal frame-plate in 120 said circuit, electro-magnets mounted upon said frame plate, an oscillating armature in said circuit, adapted to be attracted by said electro-magnets, means also in said circuit, arranged to maintain a complete electric circuit with said armature during a portion of its movement, but breaking said electric circuit during the remainder of the movement of said armature, all arranged to produce the incandescence of said incandescent body, and at a predetermined time extinguish the same irrespective of the varying speeds of the rotary contacting means of said circuit-completing and breaking device, substantially as and for the purposes set forth.

and incandescent body are disposed, a circuit-completing and breaking device in said circuit, comprising a rotary means which is subject to variable speeds, a metal frame-plate 5 in said circuit, electro-magnets mounted upon said frame plate, an oscillating armature in said circuit, adapted to be attracted by said electro-magnets, means also in said circuit, arranged to maintain a complete electric circuit with said armature during a portion of its movement, but breaking said electric circuit during the remainder of the movement of said armature, all arranged to produce the incandescence of said incandescent 10 body, and at a predetermined time extinguish the same irrespective of the varying speeds of the rotary contacting means of said circuit-completing and breaking device, and adjustable regulating devices for varying the 15 time of incandescence of said incandescent body, substantially as and for the purposes set forth.

6. In an igniting system for explosive gas-engines, the combination with a portion of the cylinder of the engine, and an igniting device connected therewith, of an incandescent body carried by said device, an electric ignition circuit in which said igniting device and incandescent body are disposed, 25 a circuit-completing and breaking device in said circuit, comprising a rotary means which is subject to variable speeds, a metal frame-plate in said circuit, electro-magnets mounted upon said frame plate, an oscillating armature in said circuit, adapted to be attracted by said electro-magnets, means also in said circuit, arranged to maintain a complete electric circuit with said armature during a portion of its movements, but breaking said 35 electric circuit during the remainder of the movement of said armature, all arranged to produce the incandescence of said incandescent body, a magnet circuit in parallel with said ignition circuit, in which said electro- 40 magnets are arranged, a re-actance coil in said circuit, all arranged to extinguish said incandescent body after a constant time interval irrespective of the varying speeds of the rotary 45 contacting means of said circuit-completing 50 and breaking device, and adjustable regulating devices for varying the time of incandescence of said incandescent body, substantially as and for the purposes set forth.

7. In an igniting system for explosive gas-engines, the combination with a portion of the cylinder of the engine, and an igniting device connected therewith, of an incandescent body carried by said device, an electric ignition circuit in which said igniting device 55 and incandescent body are disposed, a circuit-completing and breaking device in said circuit, comprising a rotary means which is subject to variable speeds, a metal frame-plate in said circuit, electro-magnets mounted upon said frame plate, an oscillating armature 60 in said circuit, adapted to be attracted by said electro-magnets, means also in said circuit, arranged to maintain a complete electric circuit with said armature during a portion of its movements, but breaking said 65 electric circuit during the remainder of the movement of said armature, all arranged to produce the incandescence of said incandescent body, a magnet circuit in parallel with said ignition circuit, in which said electro-

ture in said circuit, adapted to be attracted by said electro-magnets, an oscillating contact-bar also in said circuit, said contact-bar being arranged to maintain a complete electric circuit with said armature during a portion of its movement, but breaking said electric circuit during the remainder of the movement of said armature, all arranged to produce the incandescence of said incandescent body, and at a predetermined time, extinguish the same irrespective of the varying speeds of the rotary contacting means of said circuit-completing and breaking device, substantially as and for the purposes set forth. 70 75 80

8. In an igniting system for explosive gas-
engines, the combination with a portion of
the cylinder of the engine, and an igniting
device connected therewith, of an incan-
descence body carried by said device, an elec- 85
tric ignition circuit in which said igniting de-
vice and incandescent body are disposed, a
circuit-completing and breaking device in said
circuit, comprising a rotary means which is
subject to variable speeds, a metal frame- 90
plate in said circuit, electro-magnets mounted
upon said frame plate, an oscillating armature
in said circuit, adapted to be attracted
by said electro-magnets, an oscillating con-
tact-bar also in said circuit, said contact-bar 95
being arranged to maintain a complete elec-
tric circuit with said armature during a por-
tion of its movement, but breaking said elec-
tric circuit during the remainder of the move-
ment of said armature, all arranged to pro- 100
duce the incandescence of said incandescent
body, a magnet-circuit in parallel with said
oscillating contact-bar and said ignition-cir-
cuit, in which said electro-magnets are ar-
ranged, and a re-actance coil in said circuit, 105
all arranged to extinguish said incandescent
body after a constant time interval irrespec-
tive of the varying speeds of the rotary con-
tacting means of said circuit-completing and
breaking device, substantially as and for the 110
purposes set forth.

9. In an igniting system for explosive gas-engines, the combination with a portion of the cylinder of the engine, and an igniting device connected therewith, of an incandescent body carried by said device, an electric ignition circuit in which said igniting device and incandescent body are disposed, a circuit-completing and breaking device in said circuit, comprising a rotary means which is subject to variable speeds, a metal frame-plate in said circuit, electro-magnets mounted upon said frame plate, an oscillating armature in said circuit, adapted to be attracted by said electro-magnets, an oscillating contact-bar also in said circuit, said contact-bar being arranged to maintain a complete electric circuit with said armature during a portion of its movement, but breaking said electric circuit during the remainder 130

of the movement of said armature, all arranged to produce the incandescence of said incandescent body, and at a predetermined time extinguish the same, irrespective of the varying speeds of the rotary contacting means of said circuit-completing and breaking device, and adjustable regulating devices for varying the time of incandescence of said incandescent body, substantially as and for the purposes set forth.

10. In an igniting system for explosive gas-engines, the combination with a portion of the cylinder of the engine, and an igniting device connected therewith, of an incandescent body carried by said device, an electric ignition circuit in which said igniting device and incandescent body are disposed, a circuit-completing and breaking device in said circuit, comprising a rotary means which is subject to variable speeds, a metal frame-plate in said circuit, electro-magnets mounted upon said frame plate, an oscillating armature in said circuit, adapted to be attracted by said electro-magnets, an oscillating contact-bar also in said circuit, said contact-bar being arranged to maintain a complete electric circuit with said armature during a portion of its movement, but breaking said electric circuit during the remainder of the movement of said armature, all arranged to produce the incandescence of said incandescent body, and at a predetermined time extinguish the same, irrespective of the varying speeds of the rotary contacting means of said circuit-completing and breaking device, adjustable regulating devices for varying the time of incandescence of said incandescent body, consisting of a contact-screw mounted upon said contact-bar, a pair of oppositely arranged adjusting screws between which an end-portion of said contact-bar is movably arranged, and springs adjustably connected with said contact-bar and said armature for returning said bar and armature to their normal initial positions, substantially as and for the purposes set forth.

11. In an igniting system for explosive gas-engines, the combination with a portion of the cylinder of the engine, and an igniting device connected therewith, of an incandescent body carried by said device, an electric ignition circuit in which said igniting device and incandescent body are disposed, a circuit-completing and breaking device in said circuit, comprising a rotary means which is subject to variable speeds, a metal frame-plate in said circuit, electro-magnets mounted upon said frame plate, an oscillating armature in said circuit adapted to be attracted by said electromagnets, an oscillating contact-bar also in said circuit, said contact-bar being ar-

ranged to maintain a complete electric circuit with said armature during a portion of its movement, but breaking said electric circuit during the remainder of the movement of said armature, all arranged to produce the incandescence of said incandescent body, a magnet-circuit in parallel with said oscillating contact-bar and said ignition-circuit, in which said electro-magnets are arranged, a re-actance coil in said circuit, all arranged to extinguish said incandescent body after a constant time interval irrespective of the varying speeds of the rotary contacting means of said circuit-completing and breaking device, and adjustable regulating devices for varying the time of incandescence of said incandescent body, substantially as and for the purposes set forth.

12. In an igniting system for explosive gas-engines, the combination with a portion of the cylinder of the engine, and an igniting device connected therewith, of an incandescent body carried by said device, an electric ignition circuit in which said igniting device and incandescent body are disposed, a circuit-completing and breaking device in said circuit, comprising a rotary means which is subject to variable speeds, a metal frame-plate in said circuit, electro-magnets mounted upon said frame plate, an oscillating armature in said circuit, adapted to be attracted by said electro-magnets, an oscillating contact-bar also in said circuit, said contact-bar being arranged to maintain a complete electric circuit with said armature during a portion of its movement, but breaking said electric circuit during the remainder of the movement of said armature, all arranged to produce the incandescence of said incandescent body, and at a predetermined time extinguishing the same, irrespective of the varying speeds of the rotary contacting means of said circuit-completing and breaking device, adjustable regulating devices for varying the time of incandescence of said incandescent body, consisting of a contact-screw mounted upon said contact-bar, a pair of oppositely arranged adjusting screws between which the end-portion of said contact-bar is movably arranged, and springs adjustably connected with said contact-bar and said armature for returning said bar and armature to their normal initial positions substantially as and for the purposes set forth.

In testimony, that I claim the invention set forth above I have hereunto set my hand this 17th day of August 1907.

FREDERICK A. FELDKAMP.
